MAGNETOSTATIC DEVICE

Pierre Burstow, Paris, and Claude Monin, Villennes-sur-Seine, France, assignors to Compagnie Industrielle des Telephones, Paris, France, a French corporation

Filed Oct. 6, 1958, Ser. No. 765,474

Claims priority, application France Oct. 28, 1957
1 Claim. (Cl. 307—88)

The present invention relates to a magnetostatic device by means of which it is possible to select a single member from a plurality of members having the same characteristics. The selection is effected by means of magnetostatic relays having no moving contacts. The device is applicable notably in automatic telephony and telegraphy and in remote control.

Independently of selecting devices comprising either rotary switches or electromagnetic relays having moving contacts there is known a device, disclosed in French Patent No. 1,138,493 of December 8, 1955, an electromagnetic selecting device in which magnetostatic relays having no moving contacts are employed. In this device, the relays are controlled by a pilot blocking relay, which has certain disadvantages from the technical viewpoint.

The present invention has for its object to provide a selecting device of this type which employs magnetostatic relays and of which the operation is improved, while at the same time the cost is reduced, by virtue of the omission of the pilot relay.

The device according to the present invention is characterised by the fact that the relays are grouped in parallel and each feed through a feedback winding into a separate load, the free ends of which are connected to a common point, which is connected to the series-connected blocking windings of all the relays.

The separate resistances are so chosen that the strength of the current of one relay in the operated or active state is sufficient to prevent another relay from pulling up, but if two or more relays are simultaneously in the operated state the total current fed by the relays in the operated state is such that all the relays in the operated state return to the unoperated or inactive position. It is then the most rapidly acting relay which is the first to return to the operated state and which blocks the other relays in their inactive position, as long as it itself remains operated.

Further features and advantages of the invention will become apparent from the description hereinafter given with reference to the accompanying drawings, which show by way of example one constructional form of a device according to the invention:

FIGURE 1 illustrates diagrammatically a device according to the invention, and

FIGURE 2 is the operating diagram of the device.

In FIGURE 1, the dotted enclosures R_1 , R_2 , R_3 . . . R_n represent magnetostatic storage relays, for example of the type defined by applicants in French Patent No. 1,127,470 of May 27, 1955, and in the French Patent 1,160,506 filed on November 9, 1956, or in the corresponding United States Patent 2,946,896, for "Magneto-static Relay." Each relay comprises at least one saturable magnetic circuit on which are wound an operating

2

winding fed in series with a rectifier from an alternating-current source and control windings. Each relay comprises an output circuit, S_1 in the case of the relay R_1 , S_2 in the case of the relay R_2 . . . , S_n in the case

- 5 of the relay R_n , through which rectified current flows or does not flow depending upon the currents applied to the control windings. The saturable magnetic circuit for each relay is illustrated as an annular core and for the core associated with relay R_1 there are illustrated wound thereon feedback winding e_{11} , bias winding e_{12} , primary control winding e_{13} , holding winding e_{14} and blocking winding e_{15} in addition to an operating winding. Similar windings are provided for each of the other magnetic cores but with appropriate changes in the numerical subscripts designating particular windings. The blocking windings e_{15} , e_{25} , e_{35} . . . e_{n5} of the relays R_1 , R_2 , R_3 . . . R_n are connected in series. Connected to the output point S_1 of the relay R_1 is the feedback winding e_{11} , the other end of which is connected to an individual load r_1 . Connected to the output point S_2 of the relay R_2 is the feedback winding e_{21} , of which the other end is connected to an individual load r_2 . The same is the case with the other relays R_3 , R_4 . . . R_n . The outputs of the individual loads are connected to a common point

20 P_1 (the resistances of the links P_1P_2 , P_2P_3 . . . $P_{n-1}P_n$ being assumed to be negligible), which is in turn connected to the series blocking windings e_{15} , e_{25} . . . e_{n5} of the various relays.

Any operated relay, for example R_1 , feeds from the output point S_1 a current which flows through the negative winding feedback e_{11} , across the resistance r_1 and then through the series blocking windings e_{15} , e_{25} . . . e_{n5} . An unoperated relay does not feed any current into the blocking circuit. Connected to the output point S_2 of the relay R_2 is the feedback winding e_{21} , of which the other end is connected to an individual load r_2 . The same is the case with the other relays R_3 , R_4 . . . R_n . The outputs of the individual loads are connected to a common point

25 P_1 (the resistances of the links P_1P_2 , P_2P_3 . . . $P_{n-1}P_n$ being assumed to be negligible), which is in turn connected to the series blocking windings e_{15} , e_{25} . . . e_{n5} of the various relays.

Any operated relay, for example R_1 , feeds from the output point S_1 a current which flows through the negative winding feedback e_{11} , across the resistance r_1 and then through the series blocking windings e_{15} , e_{25} . . . e_{n5} . An unoperated relay does not feed any current into the blocking circuit. Any counterclockwise directed

30 arrow adjacent a relay winding indicates that if a current flows through the winding it tends to bring the relay to the operated condition (positive ampere-turns). On the other hand, a clockwise oriented arrow adjacent a winding indicates that if a current flows through the winding it tends to return the relay to the inactive state (negative ampere-turns).

The windings e_{12} , e_{22} , e_{32} . . . e_{n2} are bias windings of the various relays, which permit of bringing the latter to a common initial setting.

45 The windings e_{13} , e_{23} , e_{33} . . . e_{n3} are control windings which tend to bring the relays to the operated condition, while the windings e_{14} , e_{24} , e_{34} . . . e_{n4} are holding windings which tend to cause the operated relay to fall back or to maintain the relay in the inactive condition. The resistance of all the series blocking windings e_{15} , e_{25} , e_{35} . . . e_{n5} is small in relation to the individual resistance of a relay, so that the potential of the common point is only slightly different from that of the second pole of the relay.

50 The operation of the device will hereinafter be explained with reference to FIGURE 2, which is the operating diagram of a magnetostatic storage relay. The control ampere-turns $N_c I_c$ are plotted along the axis of the abscissae and the output current I_S is plotted along the axis of the ordinates. It will be assumed that FIGURE 1 represents a number of ringing relays R_1 , R_2 . . . R_n forming a group in accordance with the arrangement indicated. The bias windings of these various relays

have set the operating point at the point O. All these relays are therefore in the inactive state. If the subscriber whose ringing relay is, for example, the relay R₂ calls, there flows through his control winding e₂₃ current which gives positive ampere-turns represented by the vector C₂. The operating point changes from the point O to the point P₁, and the relay R₂ is operated or active and consequently supplies a current i. The current i produces in each of the series windings e₁₅, e₂₅ . . . e_{n5} negative ampere-turns which are represented by a vector B_T in the case of the operated relay and by a vector B_R (of the same size as B_T) for the inactive relays. It will thus be seen that the operating point changes from the point P₁ to the point P₂ in the case of the operated relay, while in the case of the inactive relays the operating point changes from the point O to the point A₁. Under these conditions, if another subscriber calls, for example the one corresponding to the relay R₃, the ampere-turns produced, which are represented by the vector C₃, will bring the operating point from point A₁ to the point P₃, but the relay R₃ will not become active.

Therefore, any operative relay blocks all the other relays of the group which are in the inactive state, as long as it itself remains operative.

Assuming now that a plurality of relays, for example the relays R₂ and R₃ have been simultaneously operated, each of them then supplies a current i and these currents will be summated to form a current 2i in the common part of the circuit, that is to say, in the series blocking windings e₁₅, e₂₅, e₃₅ . . . e_{n5}. The ampere-turns produced are represented by vectors 2B_T in the case of the operative relays or 2B_R in the case of the inactive relays, which respectively change the operating points from P₁ to the point O in the case of the operative relays and from the point O to the point A₂ in the case of the inactive relays. Therefore, the relays which are operative change to the inactive state.

It will be obvious that no two relays can ever have exactly the same internal characteristics, one of the relays being re-operated before the other and eliminating

it in accordance with what has been stated in the foregoing. The example taken here is that of a group of ringing relays. It is obvious that the invention is applicable to other groups of members, for example to the selection of a free line from a plurality of lines of like direction, and in general to the selection of a single member from a plurality of members having the same characteristics. It is also possible for the individual resistances such as r₁, r₂ . . . r_n to be included in the feedback windings themselves.

We claim:

A magnetostatic selecting device including a plurality of magnetostatic relays, each magnetostatic relay comprising a saturable magnetic circuit, a main operating winding wound on the magnetic circuit with an output connected thereto, and additional windings wound on the magnetic circuit including a control winding, a feedback winding and a blocking winding, each relay being susceptible to assume active and inactive states of operation respectively supplying different current values in its output circuit, means for applying a control current to the control windings of each of the relays to modify its state of operation, the feedback winding of each of the relays being connected in series in the output circuit of said relay, means connecting the output circuits of the relays to a common point, means connecting the blocking windings of said relays in series to said common point with said windings being so constructed and arranged that when all the relays are in the inactive state of operation a control current is applied to a control winding of one of the relays, said relay is placed in the active state of operation and its output circuit supplies a constant direct current in the blocking windings of the other relays to keep them inactive.
